HIS ATTORNEY

UNITED STATES PATENT OFFICE.

ALLEN B. CREEK, OF SAN FRANCISCO, CALIFORNIA, ASSIGNOR OF ONE-HALF TO
ANTONE J. CARDOZA, OF SAN FRANCISCO, CALIFORNIA.

CARD-CASE.

1,308,336.

Specification of Letters Patent. Patented July 1, 1919.

Application filed February 3, 1919. Serial No. 274,698.

To all whom it may concern:

Be it known that I, ALLEN B. CREEK, a citizen of the United States, and resident of San Francisco, in the county of San Francisco and State of California, have invented certain new and useful Improvements in Card-Cases, of which the following is a specification.

My invention relates to a type of card cases in which the cards may be partly ejected by means of a flexible band secured to the back of the case, passing under said cards and through an opening in the front of said case.

This type of card case is ordinarily designed to fit a vest pocket and is provided with no means for carrying a pencil of any kind. To provide a pocket for a pencil adds materially to the cost of producing the article and adds to the bulk of the same as well as preventing its general use as a pocket case. Also, a pencil carrying means of that nature is not desirable because of the inconvenience of removing the pencil therefrom and the ever-present danger of neglecting to place the pencil in said pocket after use and the consequent misplacing and loss of the same.

It is the object of my invention to so attach a pencil to the case as to satisfactorily overcome all of the objections above set forth and thereby provide a case of the character indicated which is always provided with a pencil ready for use, occupying but a small space without additional pockets, and automatically presented for use or withdrawn to a fixed position after use by the act of ejecting or replacing the cards in the case as the case may be.

With these and other objects in view, my invention consists in the novel and useful provision, construction, formation, combination and relative arrangement of parts, members and features, all as hereinafter described, shown in the drawing and finally pointed out in the claim.

The figure is a perspective view of a card case embodying my invention.

Referring now more particularly to the drawing, 1 is the body of the card case enclosed on all sides and the bottom and filled with cards 2. At 3 is shown a ribbon attached to the inside of the back of case 1 at 4, passing downwardly and under cards 2 and thence forwardly and upwardly and out of case 1 through slot 5 so that by pulling ribbon 3 out through slot 5 the cards 2 are forced out of case 1.

To the free end of ribbon 3 is attached a pencil 6 by looping the ribbon around the same and sewing the same in place, the said ribbon being of such a length that when the cards are in position in case 1 the said pencil will maintain contact with the said case 1 in a substantially horizontal position as shown.

When the cards are partly ejected for the purpose of recording data thereon by pulling ribbon 3 outwardly the pencil 6 is rendered freely available for use because the portion of ribbon 3 drawn out is substantially double the length of the exposed portion of the cards. When the cards are forced back into position in the case 1 they automatically withdraw the ribbon by forcing it downwardly into the case and thereby automatically lock the pencil in the position shown.

The cards are shown partly ejected in dotted lines at 7 and the pencil is indicated in position for use in dotted lines at 8, the ribbon being indicated at 9.

It is also pointed out that the pencil also provides a convenient and substantial handle whereby the ribbon 3 may be drawn out with a minimum of difficulty, and it also forms a stop that prevents the ribbon from being entirely withdrawn into the case 1.

It is further pointed out that a flat ribbon is used so that it is necessary to form slot 5 parallel with the top of card case 1 with the result that the pencil normally assumes a convenient horizontal position near the top of the case.

I claim:
The combination with a card case having

a flexible member attached to the inner surface and near the top of the back thereof and passing through an aperture in the front thereof and forming a loop to support cards placed therein, of a pencil attached to the free end of said ribbon and forming a stop for said ribbon when said

cards are in position in said case and freely available for use when said cards are partly ejected from said case. 10

In testimony whereof I have hereunto affixed my signature this 27th day of January, 1919.

ALLEN B. CREEK.
